UNITED STATES PATENT OFFICE.

WILLIAM EVANS DE VOE, OF CHICAGO HEIGHTS, ILLINOIS, ASSIGNOR TO THE
UNDER-FEED STOKER COMPANY OF AMERICA, OF CHICAGO, ILLINOIS, A
CORPORATION OF NEW JERSEY.

UNDERFEED-STOKER.

1,385,433.

Specification of Letters Patent. Patented July 26, 1921.

Application filed June 9, 1919. Serial No. 302,784.

To all whom it may concern:

Be it known that I, WILLIAM EVANS DE VOE, a citizen of the United States, residing at Chicago Heights, in the county of 5 Cook and State of Illinois, have invented certain new and useful Improvements in Underfeed-Stokers, of which the following is a specification.

My invention relates to under-feed stokers 10 and more particularly to ram-driving means for such stokers, and it consists in the features of construction, combination, and arrangement of parts, hereinafter pointed out and claimed.

15 Ram-operation plays an important part in the functioning of the under-feed stoker in the matter of clinkерage, among others. A slowly reciprocated ram, constantly reciprocating, tends to force the clean fuel 20 into the retort without breaking up the clinkers which form at the retort mouth; whereas (other conditions being equal) an impulsively reciprocated ram, that is, one making its in and out strokes rapidly but 25 dwelling between strokes, is very efficacious in clinker-breaking and, therefore, in keeping a clean, bright fire needing minimum supervision.

Also, the frequency of ram-reciprocation 30 is important, in that it is a factor which determines the quantity of fuel supplied, or at least the maximum and minimum ranges of fuel quantities fed to the retort in a given time.

35 Heretofore it has been known practice to operate all of the rams of a furnace battery from a single line shaft, reciprocating all of the rams in unison, slowly and constantly. Also it has been known practice to operate

40 each ram independently, equipping it with a steam engine or other motor individual to the ram and controlled by an individual valve mechanism, so that each ram can be operated through a rapid stroke-cycle and 45 then dwell for a pre-determined period, the periodicity of operation of each ram being controlled independently of that of its battery-fellows. This sort of installation, however, requires quite complex and expensive 50 equipment and in many instances is undesirable for engineering reasons.

To the best of my knowledge, it is novel with me to provide a single high-speed line shaft and connect the several rams of a fur-

nace battery therewith by mechanical means 55 each individual to its respective ram, each such mechanism operable from the constant speed line shaft for rapid reciprocation and intervening dwells of the ram, and each unit mechanism being settable to determine the 60 frequency of the reciprocation-cycle, or, conversely stated, the dwell duration.

In the mechanism herein shown, characterized as above outlined, I secure great advantage in many installations, dispensing 65 with elaborations of piping, valves, and engine equipment for each ram, enabling a single power source, such as an electric motor, to be used for driving all of the rams under best load conditions, and yet securing 70 the substantial benefits of clinker-breaking stroke-speed and of capacity-regulating individualization of the stroke periodicity of the ram, which advantages have heretofore been realized only in the more expensive 75 installations above referred to. Also I secure many advantages in the particular construction shown, in certainty of operation, ruggedness, fine adjustment, simplicity, and manufacturing and operating economy. 80

In the drawings, Figure 1 is a diagrammatic plan view showing a battery of stoker units equipped with my devices; Fig. 2 is a side elevation of one unit equipment; Fig. 3 is a plan view of the same; Fig. 4 is a section 85 on line 4-4 of Fig. 3; Fig. 5 is a detail of a ratchet wheel and guard, Fig. 6 is a detail of a modified ratchet wheel and guard construction; Fig. 7 is an inverted plan view inversion made about the shaft as an axis 90 with parts broken away showing the positive clutch mechanism; Fig. 8 is a fragment of the driving gear, and Fig. 9 is a perspective detail of the clutch block.

Each furnace unit 10, 10^a, etc., has its 95 retort 11 fed with green fuel from a hopper 12 by means of a ram which, as herein shown comprises a horizontal cylinder and frame 13 in which there works a plunger or piston 14, the connecting rod 15 of which 100 is actuated by a crank shaft 16 individual to that ram and mounted on a frame extension 13'.

Each crank shaft is actuated from a common line shaft 17 running along the furnace 105 front, suitably journaled in the frame extensions 13', and having for each battery unit a pinion 18 which meshes with a large

gear 19 loose on the crank shaft 16. A single source of motive power, typified by the motor 20, may drive the line shaft at relatively high speed, by a chain belt 21. Each drive wheel or large gear 19 is clutch-connectible with its normally free or idle crank shaft 16 by means arranged to effect such connection positively for a single rotation of the drive wheel and then to disengage; and for governing the periodicity of this connecting operation an adjustable controlling device is provided, preferably operated from a constantly running part such as the drive wheel 19 of the unit.

The clutch means specifically shown is simple and rugged. Fast on the normally idle crank shaft 16 is a clutch carrier 23, peripherally grooved as at 24. Through this carrier and across the groove there passes a block 25, slidable transversely to the carrier, this clutch block when projected engaging, and when retracted disengaging, a notch 26 in the hub portion 19' of the loose driving wheel 19, that wall of the notch which faces forwardly in the rotative direction of the gear wheel being beveled as best shown in Figs. 4 and 7. A spring 27, positioned by a small bracket 27' on the carrier 23 presses the clutch block toward wheel-engagement. The clutch block 25 is grooved as at 28 to the depth of the carrier-groove 24, one of the side walls of this groove being angularly cut or beveled to wedge-formation with the low end of the wedge facing forwardly or in the direction of wheel rotation. Movement of the clutch block is controlled by a clutch lever 30. This is pivoted on a bracket 31, close to its mounting on the frame extension base 13', the lever being spring elevated as by spring coil 32 so that its controlling blade 33 enters the hub groove 24. The controlling blade is beveled or wedge-shaped in plan (Fig. 7), with its thin end directed counter to the rotative direction of the driving wheel, this wedge-shaped blade sometimes coacting with the wedge side 29 of the clutch block groove to force the clutch block against the tension of its spring 27 to disengage said block from notch 26 in the normally loose driving wheel 19. It will be understood, however, that when lever 30 is depressed, throwing its blade 33 out of the notch 28 of the clutch block, the latter is spring-pressed inwardly so that its inner end will slip down the inclined side of notch 26 when said notch comes into register with the clutch block end, thereby engaging the carrier 23 and wheel so that wheel 19 will rotate the crank shaft until the clutch block is withdrawn from such engagement. If, however, before the connected carrier and wheel have completed a rotation, the lever 30 is spring-raised to restore the blade 33 to its normal position in the peripheral groove of the car-

rier, the inclined end of the blade will receive the beveled wall 29 of the clutch block as the latter comes to its initial position, and will retract the clutch block out of engagement with the loose wheel 19. Such is the operation of the device, automatic and adjustable governing means being provided for intermittently depressing the lever 30.

The lever 30 has a cam lug or tooth 35, in the path of rotation of the striker pin 36 carried by a ratchet wheel 37 mounted on bracket 31, this ratchet wheel being arranged to be driven counterclockwise by a pawl-arm 38, normally up-lifted by a spring 39 to an upper position where it is stopped by a lug 40 (Fig. 4), the free end of such pawl-arm being interposed in the path of a striker roller 41 carried by the hub portion of the loose wheel 19. A spring pawl 42 on the arm engages the teeth of the ratchet. Manifestly a suitable number of vibrations of the pawl-arm will effect the complete rotation of the ratchet wheel causing its striker pin 36 to depress the clutch lever 30 and allow it to spring back again. It is important, however, as a matter of refinement, that the number of vibrations of the pawl-arm requisite for a complete rotation of the ratchet wheel be variable, and that assurance be had that the ratchet wheel will never dwell with its striker pin 36 depressing the lever arm 30. To these ends I prefer to use the construction shown in detail in Figs. 2 and 5. On the arbor of the ratchet wheel I mount a shield 45, of double segment form, extending radially beyond the height of the lower teeth constituting most of the periphery of the ratchet wheel. The pawl 42 is broad enough to ride on the edge of the shield, which is so shaped as to give a curved groove or channel 46 for passage of the striker pin 36. The shield arc is preferably substantially equal to the full stroke arc of the pawl-arm, and by adjusting so that, as shown in dotted lines in Fig. 5, only some lower terminal portion of the travel of the pawl arm will carry the pawl off of the shield, one may regulate nicely the number of vibrations of the pawl-arm necessary to effect the rotation of the ratchet wheel. Preferably this adjustment is maintained by a latch member 47 engaging teeth on the rear segment of the shield. The shield may, however, be made as shown in Fig. 6, with its adjustment determined by a thumb-nut 47' locking it on the arbor.

Preferably a small number of the teeth, as indicated at 48 in Fig. 5, are made of such height that their crests may extend beyond the edge of the shield, these teeth being positioned relatively to the striker pin 36 so that one of them is bound to be within the vibratory sweep of the pawl 42 immediately before the striker pin comes into position to engage the clutch lever cam 35. Of course, 130

when any one of these teeth comes within the sweep of the pawl the ratchet wheel will be carried forward a full stroke of the pawl-arm, regardless of the position or adjustment of the shield 45, so that by no possibility can the governor wheel 37 fail to depress and release the clutch lever 30; the mechanical correlation illustrated assuring that the clutch lever will be released at a proper time to permit the clutch bar to engage the notch 26 in the loose wheel.

In a mechanism as described, especially one wherein the ram-stroke is relatively rapid, it is highly desirable that there be provided a frangible element intended to break should the ram-plunger become jammed, as may sometimes occur from sticks of wood or other over-large bodies getting into the coal hopper. I take care of this condition by connecting the clutch-element or carrier 23 with shaft 16 through a renewable breakpin 50. This is merely a cast-iron bar extending through a hole in the shaft 16 and engaging slotted cleats 51 on the clutch-member 23. A set screw 52 extending lengthwise into the shaft holds the pin 50 against displacement.

In brief résumé, the line shaft is constantly rotated at relatively high speed constantly driving the loose gears 19 for the several rams, of course at lower speed, but still with a velocity sufficient to insure a quick and impulsive reciprocation of the ram or plunger. Each freely rotating driving wheel 19 advances the appurtenant governor wheel 37 more or less each time it revolves, so that after a predetermined number of revolutions of the driving wheel 19, settable individually with respect to each unit, the affected controller wheel 37 will depress the clutch lever 30. This clutch lever depression releases clutch block 25, which engages with the drive wheel 19, thereby locking together the drive wheel and the crank shaft 16. The ram makes one reciprocation, before the completion of which the clutch lever 30 is restored to its elevated position, where its beveled blade 33 intercepts the clutch block 25, retracting the latter to clutch-disengaging position. Should the ram-plunger be jammed, the renewable pin 50 breaks, preventing injury to the gearing or other parts.

It will be understood that while I have herein described in detail a particular embodiment of my invention, for purposes of full disclosure, and some detail features of which I may specifically claim for especial advantage, many changes may be made in the particular construction and arrangement of parts without departure from the spirit of my invention in its broader aspects, within the scope of the appended claims.

What I claim is:

65 1. In combination, a reciprocable stoker

ram, a constantly running, relatively high speed driving member, connectible with said ram to reciprocate the latter with a quick stroke, and means controlled by said driving member for making and breaking such connection at intervals and governing the frequency of ram-reciprocations.

2. The combination with an underfeed stoker battery comprising a plurality of reciprocal retort-feeding rams each having a crank shaft, of driving wheels loose on said crank shafts, a line shaft having connection to drive all of said driving wheels rapidly, whereby the line shaft and driving wheels are in constant rotation, and means for intermittently connecting each crank shaft to its drive wheel to govern the frequency of quick reciprocations of the rams.

3. The combination with an underfeed stoker battery comprising a plurality of retort-feeding rams each having a crank shaft, of driving wheels loose on said crank shafts, a line shaft having connection to drive all of said driving wheels, whereby the line shaft and driving wheels are in constant rotation, and means for intermittently connecting each crank shaft to its drive wheel at predetermined and variable intervals.

4. The combination with a battery of underfeed stokers each having a ram and a crank shaft, of driving gears loose on said crank shafts, a line shaft, means on said line shaft for driving said gears, means individual to each stoker for connecting the gear to its crank shaft at intervals, and means controlled by the rotation of the loose gear governing the periodicity of such connection.

5. In an underfeed furnace, the combination with the ram and its crank shaft, of a constantly rotating part normally disconnected from the crank shaft, means for effecting operative connection between said constantly rotating part and said crank shaft, and governing means controlled by the constantly rotating part for intermittently operating said connecting means.

6. Ram operating means for underfeed stokers comprising, in combination with the ram and its crank shaft, a constantly rotatable member, a clutch for connecting said rotatable member with said crank shaft, and clutch controlling means comprising a part adjustable to cause clutch engagement after a predetermined number of rotations of the constantly rotating means.

7. Ram driving means for underfeed stokers comprising, in combination with the reciprocable ram and its crank shaft, a gear wheel loose on the crank shaft, constantly rotatable means for driving said gear wheel, clutch means for engaging said gear wheel with its crank shaft, a clutch-controlling lever, and a governor wheel controlling said lever by its rotary movement, and rotarily

moved by one of the constantly rotating parts.

8. Ram driving means for underfeed stokers comprising, in combination with the reciprocable ram and its crank shaft, a gear wheel loose on the crank shaft, constantly rotatable means for driving said gear wheel, clutch means for engaging said gear wheel with its crank shaft, a clutch-controlling lever, a governor wheel controlling said lever by its rotary movement, and rotarily moved by one of the constantly rotating parts, and means for adjusting the extent of movement of said governor wheel engaged by each rotation of said parts.

9. In a mechanism of the character described, the combination with the ram crank shaft, a constantly rotatable part for intermittent connection therewith, a clutch for effecting such connection, and a clutch lever controlling said clutch, of a governor wheel controlling said clutch lever and comprising a ratchet toothed member having lower teeth and higher teeth, a shield to extend radially beyond the lower teeth but not the higher

teeth, and a ratchet member for engaging teeth left exposed by the shield, said ratchet member operable by a constantly rotating part.

10. In combination a reciprocable stoker-ram, a constantly-running relatively high-speed driving member connectible with said ram to reciprocate the latter with a quick stroke, and means controlled by said driving member for effecting connection between the ram and driving member to impart a single stroke to the ram at predetermined intervals.

11. The combination with a battery of underfeed stokers each having a ram and a crank shaft, of a constantly-driven line shaft for driving said crank shafts, means associated with each crank-shaft for connecting it with the line shaft to receive a single rotation therefrom, and means associated with each crank shaft and driven from the line shaft for operating said connecting means at variable predetermined intervals.

WILLIAM EVANS DE VOE.
